(57) **CLAIM**

The ornamental design for a handheld medical instrument, as shown and described.

DESCRIPTION

FIG. 1 is a front, left side perspective view of a handheld medical instrument;

FIG. 2 is a back, right side perspective view of the instrument of FIG. 1;

FIG. 3 is a back elevational view of the instrument of FIG. 1;

FIG. 4 is a front elevational view of the instrument of FIG. 1;

FIG. 5 is a left side elevational view of the instrument of FIG. 1;

FIG. 6 is a top view of the instrument of FIG. 1; and, FIG. 7 is a bottom view of the instrument of FIG. 1.

Features illustrated with the broken lines form no part of the claimed design and are merely to illustrate an exemplary environment for the portion illustrated with solid lines.

1 Claim, 6 Drawing Sheets

Related U.S. Application Data

a division of application No. 29/698,791, filed on Jul. 19, 2019, now Pat. No. Des. 1,005,484.
